Inventor

UNITED STATES PATENT OFFICE.

SAM RUBIN, OF NEW ORLEANS, LOUISIANA.

TRAY.

SPECIFICATION forming part of Letters Patent No. 777,921, dated December 20, 1904.

Application filed August 13, 1904. Serial No. 220,674.

To all whom it may concern:

Be it known that I, SAM RUBIN, a citizen of the United States, residing at New Orleans, in the parish of Orleans and State of Louisiana, 5 have invented new and useful Improvements in Trays, of which the following is a specification.

My invention pertains to trays for use in trunks, packing-boxes, and the like; and it 10 has for its object to provide a tray adapted to hold trimmed and other hats in such manner that a large number of hats may be expeditiously placed in and removed from a trunk or box without liability of the hats being injured in any way, either incident to the packing or unpacking of the trunk or box or when 15 the same is roughly handled by baggage men.

The novel tray is designed more particularly for use in the trunks of traveling salesmen carrying lines of trimmed hats with a 20 view of enabling said salesmen to quickly and easily exhibit their samples; but it may obviously be used to advantage in packing hats in closets, bureau-drawers, and other receptacles.

With the foregoing in mind the invention will be fully understood from the following description and claims when taken in connection with the accompanying drawings, forming 25 part of this specification, in which—

Figure 1 is a top plan view of a tray embodying my invention, the same being shown with a portion of its body or platform broken away. Fig. 2 is a side elevation of the tray, 30 with a hat shown by dotted lines in proper position thereon. Fig. 3 is a detail perspective view of one of the hat-engaging devices of the tray removed. Fig. 4 is a detail perspective view illustrating a portion of one of 35 the bars for holding the hat-holder of the tray down on the platform or body thereof, and Fig. 5 is a similar view of a portion of the other bar for such purpose.

Similar letters designate corresponding 40 parts in all of the views of the drawings, referring to which—

A is the body or platform of the tray constituting the present and preferred embodiment of my invention, the said body or plat-

form being preferably imperforate, as shown, 50 although it might be made of open-work material without involving a departure from the scope of my invention.

B B are hollow posts, preferably of metal, 55 fixed to and rising from the body or platform adjacent to the corners thereof, and B' B' are hollow posts fixed to and rising from the body or platform at intermediate points adjacent to the side edges thereof. The said posts B B' are respectively provided with an aperture 60 a and a stud b, carried by a spring-strip c, as best shown in Fig. 2.

C C are vertically-adjustable rods disposed in the posts B and having apertures d at intervals in their length to receive the studs b, 65 and C' C' are vertically-adjustable rods disposed in the posts B' and having apertures d to receive the studs b. The rods C and C' are provided at their upper ends with seats e, designed to receive and be connected to the 70 ends of cross-bars D, preferably of wood, and the rods C are also provided at their upper ends with upwardly and inwardly extending lips f. These lips f are designed when the body or platform of another tray is placed on 75 the bars D of that shown to hold such other tray against casual endwise movement.

In virtue of the construction thus far described it will be observed that the bars D may be adjusted vertically and adjustably 80 fixed at various points above the body or platform A to suit the height of hats to be accommodated between the body or platform of the tray shown and the body or platform of another tray to be superposed on that shown. 85

E is a bar arranged longitudinally on the upper side of the body or platform A, adjacent to one longitudinal edge thereof, and having transverse corrugations g at intervals of its length.

F is a bar arranged longitudinally on the upper side of the body or platform A, adjacent to the other longitudinal edge thereof, and G is a hat-holder which the bars E and F are designed to detachably connect to and hold 95 down on the body or platform A. The bar E is tacked or otherwise fixed to the platform or body A, while the bar F, which is pro-

vided with transverse corrugations *h*, is de-
signed to be swung vertically to and from
the upper side of the body or platform. Said
bar *F* has lateral arms *i* hinged at *j* to the
upper side of the platform or body *A*, and it
is held down on the platform or body when
desired through the medium of resilient fin-
ger-pieces *k*, which are pivoted at *l* to the
platform or body and are arranged to be
swung horizontally on and off the bar *F*.
When the said finger-pieces *k* are on the bar
F, as shown in Fig. 1, the bar will obviously
be held down on the platform or body *A*, while when the finger-pieces are swung off
of the bar the bar is free to be swung up-
wardly from the body or platform for a pur-
pose presently set forth. It will be noticed
that two bars *E* are shown in Fig. 1, the bar
E at the top of the view being designed for
use in connection with an additional hat-
holder. (Not illustrated.)

The hat-holder *G*, as shown in Figs. 1, 2,
and 3, is preferably made up of a base-frame
m, formed by two rings *n* and *p*, a frame *q*,
connected to and extending upwardly from
the inner ring *p*, bars *r*, formed integral with
the frame *q*, fixed to the inner and outer rings
p and *n* of the base-frame *m* and designed to
be placed at their ends in the corrugations of
the bars *E* and *F*, parallel rock-shafts *r'*, jour-
naled in suitable bearings on the base-frame
m and carrying cranks *s* *t*, angular arms *u*,
fixed to the rock-shafts and terminating at
their outer ends in points, a bar *v*, fixed to
the upper portion of the frame *q*, coiled
springs *w*, connecting the cranks *s* of the
rock-shafts and the inner ring *p* of the base-
frame *m*, a lug *x*, carried by the arm or crank
t of one rock-shaft *r'*, and a notched bar *y*,
pivotally connected to the crank *t* of the other
rock-shaft *r'* and arranged to be placed in en-
gagement with the said lug *x*, as best shown
in Fig. 2, with a view of adjustably fixing the
arms *u* against outward movement.

In virtue of the construction of my novel
hat-holder it will be observed that when the
pointed arms *u* are swung inwardly against
the action of the springs *w* by pressure ap-
plied to the cranks *t* a hat may be quickly
and easily placed with its crown resting over
the frame *q* and the arms *u*, as shown by
dotted lines in Fig. 2; also, that when pres-
sure is removed from the cranks *t* the shafts
r' will be rocked in the directions indicated by
arrows by the springs *w*, and hence the arms
u will engage and securely hold the hat.
When the size of the hat-crown renders it
necessary, the outward movement of the arms
u may be limited by placing the notched bar
y in engagement with the lug *x*, this with a
view of preventing the said arms *u* from in-
juring the hat. Outward movement of the
arms *u* is also limited by the frame *q*, as
shown in Fig. 2, while inward movement of

said arms is limited by the bar *v*, and hence 65
the arms are prevented from catching into
each other. To remove the hat from the
holder, it is simply necessary to press the
cranks *t* toward each other, so as to disengage
the arms *u* from the hat-crown, and then lift 70
the hat off of the holder and tray.

The hat-holder *G* is placed on the body or
platform *A*, while the bar *F* is in a raised po-
sition, the bars *r* being placed with their adja-
cent ends in corrugations of the bar *E*, while 75
their opposite ends are arranged to enter cor-
rugations in the bar *F*. Said bar *F* is then
swung downwardly and secured against the
upper side of the body or platform *A* through
the medium of the finger-pieces *k*, when, as 80
will be readily observed, the hat-holder and
the hat will be securely connected to the body
or platform and will not be liable to casually
move under ordinary conditions.

It will be readily appreciated from the fore-
going that a hat may be quickly and easily
attached to my novel tray without liability of
the hat being injured; also, that when a plu-
rality of my novel trays are superposed or
arranged side by side there is no liability of 90
the hats which they carry being pressed out
of shape, worn, or injured. It will further
be appreciated that trays constructed in ac-
cordance with my invention and carrying
hats may be quickly and easily placed in and
removed from a trunk or the like, and from
this it follows that a salesman may quickly
and easily unpack his trunk and display the
hats to the best advantage and may as quickly
and easily repack the trunk subsequent to the
exhibition of the line of hats, and this without
handling the hats or deteriorating the same
in any manner whatsoever.

While I have shown but one hat-holder *G*
in connection with the platform or body *A*, it
is obvious that a number of hat-holders may
be used in combination with said body or plat-
form *A* and the bars *E* and *F*. It will fur-
ther be noted that two or more pairs of bars
E and *F* may be used on the body or platform
A, in which event the hat-holders will be dis-
posed in parallel series.

When a number of trays constructed in ac-
cordance with my invention are each equipped
with a plurality of hat-holders *G*, it will be
apparent that the trays will not only protect
trimmed hats against injury, but will also
contribute materially to the capacity of a
trunk for the purpose of carrying trimmed
hats in such manner as to preclude deteriora-
tion of or injury to the same.

I have entered into a detailed description
of the construction and relative arrangement
of the parts embraced in the present and pre-
ferred embodiment of my invention in order
to impart a full, clear, and exact understand-
ing of the said embodiment. I do not desire,
however, to be understood as confining my-

self to such specific construction and relative arrangement of parts, as such changes or modifications may be made in practice as fairly fall within the scope of my invention 5 as claimed.

Having described my invention, what I claim, and desire to secure by Letters Patent, is—

1. In a tray, the combination of a body or 10 platform, a bar fixed on the body or platform and having a socket, a bar connected to the body or platform and movable toward and from the upper side thereof and also having a socket, and an article-holder disposed on the 15 body or platform and having bars removably placed in the sockets of the bars on said body or platform.

2. In a tray, the combination of a body or 20 platform, a bar fixed on the body or platform and having a socket, a bar connected to the body or platform and movable toward and from the upper side thereof and also having a socket, adjustable means for normally holding the latter bar against the upper side of 25 the body or platform, and an article-holder disposed on the body or platform and having bars removably placed in the sockets of the bars on said body or platform.

3. In a tray, the combination of a body or 30 platform, a bar fixed on the body or platform and having a socket, a bar having arms hinged to the body or platform, whereby it is adapted to swing toward and from the same, and also having a socket, a resilient 35 finger-piece pivoted to the body or platform and arranged to be swung on and off the latter bar, and an article-holder disposed on the body or platform and having bars removably placed in the sockets of the bars on said body 40 or platform.

4. In a tray, the combination of a body or 45 platform, a bar fixed on said body or platform and having transverse corrugations forming sockets, a bar having transverse corrugations forming sockets and also having arms hinged to the body or platform, whereby it is adapted to swing toward and from the same, a resilient 50 finger-piece pivoted to the body or platform and arranged to be swung on and off the latter bar, and an article-holder disposed on the body or platform and having bars removably placed in corrugations or sockets of the bars on said body or platform.

5. In a tray, the combination of a body or

platform, a bar fixed on the body or platform 55 and having a socket, a bar connected to the body or platform and movable toward and from the upper side thereof, and also having a socket, and a hat-holder disposed on the body or platform and comprising a main frame 60 having bars removably placed in the sockets of the bars, and spring-actuated arms pivoted to the frame and having outwardly-directed points adapted to engage a hat-crown.

6. In a tray, the combination of a body or 65 platform, a bar fixed on the body or platform and having transverse corrugations forming sockets, a bar having transverse corrugations forming sockets and also having lateral arms hinged to the body or platform, a finger-piece 70 pivoted to the body or platform and arranged to be swung on and off of the latter bar, and a hat-holder disposed on the body or platform and comprising a base-frame, a frame extending upwardly from the base-frame, bars connected to the frame and arranged to be placed in corrugations of the bars on the body or 75 platform, and spring-actuated arms pivoted to the frame and having outwardly-disposed points adapted to engage a hat-crown. 80

7. A hat-holder comprising a frame, rock-shafts journaled in the frame and having cranks *s t*, springs interposed between and connecting the frame and the cranks *s*, and arms fixed on the shafts and having outwardly-directed points adapted to engage a hat-crown. 85

8. A hat-holder comprising a base-frame, a central frame rising from the base-frame, rock-shafts journaled in the base-frame and having cranks *s t*, springs connecting the base-frame 90 and the cranks *s*, arms fixed on the rock-shafts and having outwardly-directed points, a lug on one of the cranks *t*, and a notched bar pivoted to the other crank *t* and adapted to engage said lug. 95

9. A tray comprising a body or platform, an article-holder secured on the body or platform, bars disposed above the platform, and extensible posts interposed between the body or platform and the said bars; some of the 100 said posts having lips at their upper ends.

In testimony whereof I have hereunto set my hand in presence of two subscribing witnesses.

SAM RUBIN.
